UNITED STATES PATENT OFFICE.

CHARLES BORDEN CHASE, OF FALL RIVER, MASSACHUSETTS.

LOOM.

1,282,378.

Specification of Letters Patent.

Patented Oct. 22, 1918.

Application filed June 30, 1915. Serial No. 37,154.

To all whom it may concern:

Be it known that I, CHARLES BORDEN CHASE, a citizen of the United States, residing at Fall River, in the county of Bristol and State of Massachusetts, have invented certain new and useful Improvements in Looms, of which the following is a specification, reference being had therein to the accompanying drawings.

10 My invention relates particularly to looms, and more particularly to power-driven looms having a jacquard mechanism for operating the pattern heddles, and a drop-box operated by a pattern chain to give the desired picks.

15 It is common practice, in the manufacture of bed spreads, to use a power-driven loom having a jacquard operated pattern warp, a heald shaft warp; a coarse or pattern filling, and a fine or binder filling; the order of the 20 weave being two picks of coarse filling and two picks of fine or binder filling; the picks being determined by a chain controlling the operation of the shuttle drop-box. The bed spread resulting is described as of "satin bed 25 spread construction", the pattern appearing as if it were laid upon a plain ground.

But in so far as applicant is aware, no bed spread of said construction, has ever had introduced into this plain ground, distinguishing or colored filling threads for the 30 purpose of forming therein, for example, with parallel distinguishing or colored warp threads, a cross barred design such as illustrated in some of the drawings referred to 35 hereinafter. And further there is no loom, as at present constructed, adapted without substantial changes, to produce the above-described bed spread, with such distinguishing filling thread or threads.

40 One of the objects of my invention is to produce in the above-mentioned loom, mechanism whereby a colored or distinguishing filling thread may whenever and wherever required by the design, be substituted 45 for a binding filling thread, and be woven into the ground.

It is obvious that if the colored filling thread were to be woven with great frequency, say every fourth pick, the shuttle 50 drop-box could be easily and perfectly operated by a chain; but should the design require that the substitution of the filling thread should be made only after one hundred or one thousand picks, a pattern chain

would have to be of such inordinate length 55 and weight, alone, as to render itself utterly useless.

To cover such a contingency, a jacquard card, corresponding to the picks of colored filling required, is suitably punched, and by 60 means of levers, links, etc., the jacquard knife or griff instead of the pattern chain, operates the shuttle drop-box; hence between the jacquard indication, and that of the pattern chain, the shuttle drop-box presents to 65 the race the proper shuttles of course, fine and colored filling threads, in the manner required by the design, whether the colored filling thread be introduced only once or any other number of times, provided the pattern 70 chain of itself could not practically bring about the fulfilment of this requirement.

In the drawings illustrating the principles 75 of my invention, and the best modes now known to me of embodying the same,

Figure 1 shows the lower left-hand quarter of a design for a bed spread which embraces one feature of my invention, viz, distinguishing colored filling threads, that cannot be practically indicated by a pattern 80 chain.

Fig. 2 is the reversed portion *a, b*, of the above design, actually laid out on pointed paper to show the impracticability of using only a pattern chain to indicate the distinguishing colored filling thread required by 85 the design.

Fig. 3 represents diagrammatically the mechanism required and invented by me, for operating the drop-box to weave a bed 90 spread having one or more colored filling threads that cannot be practically indicated by the pattern chain of the loom.

Fig. 4 is a sectional view on line 4-4, 95 Fig. 3.

The new feature shown in the bed spread 1, Fig. 1, is the distinguishing colored filling thread or threads as 2, 2', 2'', 2''', 2''''. It is here combined with colored warp threads as 3, 3' to form a pleasing lattice design in 100 ground upon which raised jacquard-formed figures 4, 4, appear to be laid. The weave employed requires two warps, one a pattern warp, and the other the heald shaft warp; and two kinds of filling, one coarse or pattern filling, and a fine or binder filling; the order of weave being two picks of coarse and two picks of fine. In other words, as will be 105

understood by those skilled in the art, the bedspread here shown is what is well known as "satin bedspread construction."

All of the filling threads except those distinguished as by color, are controlled by the pattern chain 5, Fig. 3, of the box motion, whose construction is well understood but may be briefly described as follows: Power segment gears 6, 7, operate in opposite directions; while vibrator gears 8, 9, located between the segment gears, have teeth and spaces to cause them to revolve or not, as the teeth or spaces are adjacent to the teeth or spaces on the power segment gear. These vibrator gears 8, 9, are mounted upon studs 10, 10^x fixed to the vibrator levers 11, 12; and the latter in turn, are supported at one end by a stud 13 attached to the loom; the other end of one lever 11 being connected by rod, 14, to the small lever 15 which bears upon the alternate bars 16 and rolls 16^a of the chain 5; while the other vibrator lever 12 is connected by a wire 24 to colored filling thread indicating mechanism, later to be described. Vibrator bars 17, 18, are pivoted to their respective vibrator gears 8, 9, and to bell crank box levers 20, 20^x, Figs. 3 and 4, fulcrumed, in reverse direction, on a rigid pin *a*, with the upright arm *b* of the lever 20 connected with one vibrator bar 17, and the upright arm *c* of the other lever 20^x, to the vibrator lever 18, in the usual way. A lever 23 provided with a give-way joint *d*, is pivotally connected with the two levers 20, 20^x, by two parallel connectors *e*, *f*, and also with the lower end of the box lifting rod 22, on the top of which are supported shuttle boxes 21, 21^a, and 21^b, each to receive a shuttle respectively for coarse filling, fine filling, and colored or distinguishing thread.

Obviously, the lever 23 acts as a lever of the first or the second order, to raise the shuttle box rod 22, accordingly as it is operated by the bell crank lever 20 and the connecting rod *e* with fulcrum at *d*, or by the bell crank lever 20^x and the connecting rod *f*, with fulcrum at *g*. In the former case, the fulcrum being at *b*, and in the latter, at the pivot *g*, the lever 23 by whichsoever connecting rod operated, has, for its fulcrum, the pivot at the bottom of the other connecting rod; and the pivots *d* and *g* bear such relations to each other that when the upper arm *b* of the bell crank lever 20 is drawn back toward its vibrator gear 8 by the vibrator bar 17, the rod 22 is lifted a distance equal to one box, and when the bell crank lever 20^x is drawn back by its vibrator bar 18 and the vibrator gear 9, the lifting rod 22 is raised a distance equal to two boxes. While the connecting rods *e*, *f*, swing on their pivots at either end, ways, not shown in this diagrammatic Fig. 3, convert their motions into the reciprocating motion required by the box rod.

By this structure the shuttle box rod may be moved from a stated position a distance equal to one or two boxes, and required to weave the bedspread herein described.

The other vibrator lever 12 is connected as 70 by a single wire 24, bell crank lever 25, Fig. 5, and roller 26, to a drop box hook 27 and other parts of a jacquard mechanism 28, appropriated and adapted by me, to accomplish one of the objects of my invention. 75 This jacquard mechanism 28 has its usual card cylinder 29, heddle hooks 30, needles 31 and griff blades 32, 33, for operating the hooks; also a series of cards 34 for operating such pattern heddles 35 as are required by 80 the design. It is to be remembered here that through suitable but well understood apparatus, not shown, the jacquard mechanism operates upon each pick, while the pattern chain 5 is moved only on every other 85 pick.

A reference to the design shown in Fig. 2, where the space between adjacent parallel lines indicates filling threads and corresponding picks, shows, for example, that the 90 colored filling threads 2, 2', 2'', 2''', 2'''', are introduced on the following picks: 2, the 5th and 6th; 2', the 89th and 90th; 2'', the 97th and 98th; 2''', the 181st and 182d; 2'''', the 189th and 190th; etc. While the two 95 coarse and two fine picks repeat every fifth pick and are controlled by the alternate bars and rolls forming the chain pattern 5, as already pointed out, the substituted colored filling picks are controlled by the following 100 described mechanism:

In the end portion of each card, as 36, of the pattern design corresponding to the picks calling for a colored filling thread *i.e.* the 5th and 6th—the 89th and 90th—etc., is 105 punched a drop-box hole 38 to receive a drop-box needle 39 which controls the drop-box hook 27, so that the latter is lifted by a griff blade 33 whenever a card as 36 with a drop-box hole 38 is presented to the needle 39, and consequently the vibrator lever 12 connected to the hook 27, is raised together with the vibrator gear 9 which through the segment gear 6, vibrator bar 18 and connecting box levers 20 raises or lowers, as the case 110 may be, the drop-box so that the shuttle containing the colored filling thread is in line with the race 40.

To be more specific, when the box mechanism is inactive, the chain lever 15 is simply 120 resting upon a bar as 16, in Fig. 3, and the shuttle box 21 for, say, coarse filling thread, is in proper position in relation to the race-way 40, for two coarse picks. After the two coarse picks, the chain 5 moves the adjacent 125 roll 16^a, lifts the lever 15, which in turn, raises the vibrator lever 11, whose vibrator gear 8 moves up into engagement with power segment gear 6. The rotation of the latter, partially rotates the vibrator gear 8; 130

the vibrator 17 moves inward, causing the bell crank lever 20, through the connecting rod *e*, to move the lifting lever 23 about *d* as a fulcrum, and raise the next box 21^a containing fine filling thread, into position opposite the race-way. After two picks of fine filling, the boxes are returned to a normal position by the lower power gear 7, as is the case after every two picks of the loom. But it is while chain lever 15 is, as now, on a bar 16 of the chain, that the card, as 36, of the jacquard mechanism, representing the fifth pick, is in position, and its drop-box hole 38 receives the drop-box needle 39. When this happens, the griff blade 33 engages and lifts the drop-box hook 27, and by means of bell crank lever 25 and wire 24, raises the drop-box vibrator bar 18, and its gear 9, the latter engaging the power segment gear 6. The vibrator bar 18 is moved together with the bell crank lever 20^x, the drop-box lever 23 is moved about its fulcrum *g*, viz, the other pivotal connection between the lifting lever 23 and the connecting rod *e*, and the box is raised two box positions, so that box 21^b having the shuttle with colored filling thread, is in position to be delivered by the fifth pick to the race-way; the lever 15 still resting on its chain bar 16, and the vibrator rod 17, bell crank lever 20 and connecting rod *e* remaining stationary by reason of lock-knife mechanism, not shown but well understood. The 6th pick for the colored thread is brought about by the repetition of this operation, due to the needle hole 38^x in the next card 37. For the 7th and 8th and the succeeding picks, until the 89th and 90th are reached, the alternate bars and rolls of the chain have the entire control of the coarse and the fine filling threads, and none of the jacquard cards operating the pattern heddles and corresponding to picks 7 to 88 inclusive has a drop-box needle hole, hence the drop-box mechanism, during this period, is inoperative in so far as moving the drop-box into position for delivering the filling thread to the race-way. However, the cards for the 89th and 90th picks which deliver the colored filling, are each provided with a drop-box hole, and in a manner already pointed out, set in operation the drop-box mechanism which delivers the two picks of colored thread in place of the two picks of plain filling that, but for the operation of the needle holes and connecting apparatus of the jacquard mechanism, would have resulted from the engagement of the chain lever with the bar rather than the roll of the pattern chain.

The method of weaving the subsequent fill-

ing threads required by the design is the same as that already described and no further description of it in detail seems necessary.

It is to be understood that applicant for the sake of clearness has omitted details of structure which those skilled in the art must know are necessarily present, such, for example, as lock-knife mechanism to engage and keep the vibrating levers in stationary position while the segment gears revolve; or duplicate mechanism for raising and lowering the shuttle boxes at the other end of the loom, with obviously unimportant modifications.

From what has been said, it is plain that by providing the proper cards of the jacquard mechanism with independent drop-box holes and suitably controlled drop-box mechanism, one or more colored filling threads may be woven by picks utterly beyond the control of the pattern chain.

Desiring to protect my invention in the broadest manner legally possible,

What I claim is:

1. In a loom having a jacquard mechanism and a drop-box for shuttles for weaving backed fabrics, the combination for timing and setting into operation the power means for operating the drop-box comprising vibrated gear mechanism operatively connected to the drop-box, a pattern chain operatively connected to the vibrated gear mechanism, a drop-box hook, a jacquard card cylinder, a jacquard needle operatively connected with said drop-box hook for operating the drop-box, a needle card being one of the jacquard cards, all adapted to introduce into the design of the fabric a distinguishing filling thread after the completion of a number of picks in each repeat of so much of the filling design as is controlled by the movement of the pattern chain.

2. A loom comprising the ordinary jacquard mechanism and pattern chain, means controlled by the pattern chain for weaving the plain filling threads, a drop-box, a drop-box needle, operative connections between the drop-box needle and the drop-box, means upon the jacquard cards of the jacquard mechanism comprising apertures for operating said drop-box to substitute a distinguishing filling thread for the plain filling thread.

In testimony whereof I hereunto affix my signature in the presence of two witnesses.

CHARLES BORDEN CHASE. 120
